UNITED STATES PATENT OFFICE.

RICHARD B. SHELDON AND JOSEPH V. PEACOCK, OF SHORTSVILLE, N. Y.

FORCE-FEED DISTRIBUTER FOR FERTILIZERS.

SPECIFICATION forming part of Letters Patent No. 226,121, dated March 30, 1880.

Application filed January 17, 1880.

To all whom it may concern:

Be it known that we, RICHARD B. SHELDON and JOSEPH V. PEACOCK, of Shortsville, Ontario county, in the State of New York, have 5 invented a new and useful Improvement in Force-Feed Distributers for Fertilizers; and that the following is a full and exact description of the same.

The mechanical distribution of such fertilizers as the phosphates has always been troublesome and uncertain because of the sticky character of the compound, and the operation of force-feed devices, for the same reason, has not proved entirely satisfactory.

15 We propose to obviate the difficulties heretofore encountered by a cutting action upon the mass, which shall thus separate it, and by positive means forcibly feed it through appropriate channels to the ground. This is the 20 main object of our improvement; but we also have sought to construct the device with a view to cheapness and facility in manufacture and easy removal of all its parts, whether for cleansing or repairs.

25 That others may fully understand our invention, we will particularly describe it, having reference to the accompanying drawings, wherein—

Figure 1 is a perspective view of our machine in operative condition, the hopper and distributive mechanism being omitted. Fig. 30 2 is a vertical section of the same. Fig. 3 is a perspective view of the bed-plate or frame. Fig. 4 is a bottom plan of the same. Figs. 5, 35 6, 7, and 8 are the several parts detached.

A is the bed-plate or frame, provided with projecting lugs *a a* for attachment to the frame-work of the machine. At its center it has an upward-projecting hollow bearing, *b*, 40 having grooves or slits *c* longitudinally through it to receive a spline or feather on the short shaft *B*, which is fitted to said bearing to prevent the same from revolving. Concentric with the axis of said bearing *b* there is a 45 raised peripheral rim or flange, *d*, forming on said bed-plate a circular cup, and at one side, within said rim, there is a discharge-opening, *e*.

Outside the flange *d*, and forming a part of 50 the frame *A*, there are two open bearings, *f f*, to receive the hub of the bevel-pinion *C*,

through which motion is transmitted from the driving-shaft *D* to the feed mechanism. For this purpose the pinion *C* is provided with a square opening through it axially to receive 55 said shaft.

A circular cup or trough, *E*, sets upon the edge of the rim *d* and slides thereon, being kept in center by a rib or flange upon the exterior bottom of the cup *E*, which may be fitted to revolve either inside or outside of the rim *d*.

On the external bottom there is a peripheral row of cog-teeth, which mesh with the pinion *C*, and the cup *E* is thereby rotated when 65 the machine is in operation.

Within the cup *E* there is the feeder *F*, consisting of a volute plate or frame, hollow about the center, and provided with a central stud, *B*, fitted to the interior of the bearing *b*, and 70 provided with longitudinal ribs or splines to fit the grooves *c* and prevent the feeder *F* from revolving.

The inner edge, *h*, of the feeder is sharpened or made to shear, to facilitate the separation 75 of the phosphate or other substance. The feeder *F* also serves to keep the cup *E* in place, and they are both secured against accidental displacement by a wedge-shaped button, *G*, which is pivoted to the under side of 80 the frame *A*, and may be pushed into a notch, *i*, cut in one of the longitudinal ribs of stud *B*. The stud *B* also projects above the upper surface of the feeder *F*, to serve as an attachment for the cleaner *H* and shear-plate *I*. 85

The cleaner revolves upon the stud *B* with the cup *E*, because the projecting blades *k* engage with lugs *m*.

The shear-plate *I* is stationary, being restrained from revolving by lugs *n n*, which engage with the locking-pin *p*, which projects from said stud *B*, to prevent the displacement 90 of the cleaner or guard-plate when the machine is in operation.

To permit the placing of the cleaner a radial notch, *q*, may be made in said plates or the pin *p* may be removable, or it may be made with an enlargement at the base of the upper portion of the stud *B* of any reasonable size, and the central orifice of the cleaner *H* 95 of sufficient size to fit snugly about it and be held in place by the shear-plate *I* and pin *p*. 100

We prefer the radial notch, because there is then no liability to loss of so small a part as the pin *p*.

In the shear-plate *I* the radial notch is made close to the left-hand lug *n*, and the action of the machine carries said plate to the left until the pin *p* strikes the right-hand lug, and the plates are securely held in place.

As the machine is revolved the blades *k* at each revolution act against the plate *I* and shear off the bottom of the mass of phosphate or other fertilizing substance, and the action of the revolving cup *E* carries it within the projecting arm of the volute feeder *F*, and it is thereby discharged into the opening *r* in the bottom of said cup, whence it either falls into the discharge-opening *e* or upon the bottom of the frame *A*, and in the latter case it is pushed into the discharge *e* by a scraper, *t*, on the exterior bottom of the cup *E*.

Those portions of this apparatus which are shown herein and relate to the bed-frame, to the mode of securing the parts together by means of a stud from the scroll-feeder, which passes through the tubular hub of said frame and lock underneath the same, to the scroll-feeder with a continuous flange or rim, to a cleaner attached to the under surface of the revolving hopper, and to the open hanging bracket for the bearings of the driving-pinion were the sole invention of Richard B. Sheldon, and are included in an application for Letters Patent filed of even date herewith. These are therefore hereby disclaimed as joint inventions.

Having described our invention, what we claim as new is—

1. The rotating cup *E*, provided with an open or perforated bottom, and having within it a loose rotating cleaner-plate, *H*, and a stationary feeder, *F*, whereby the central portion is supported and the bottom of the mass is suc-

cessively sliced away, removed, and discharged in a continuous stream, as set forth.

2. The bed *A*, constructed with hollow central hub, as described, the rotating cup *E*, and cleaner *H*, and the stationary feeder *F* and shear-plate *I*, combined with the stud *B*, projecting above and below the feeder *F*, and locking-button *G* and pin *p*, whereby all the parts are securely held together.

3. The revolving cleaner *H*, provided with one or more shearing-arms, *k*, acting against and beneath a stationary shear-plate, *I*.

4. The hollow bearing or hub *b*, provided with the internal longitudinal groove or grooves *c*, combined with the hub *B*, provided with corresponding splines, and the locking-button *G*, substantially as set forth.

5. The revolving cup *E*, provided with lugs *m*, combined with the loose cleaner-plate *H*, the projecting arms *k* whereof engage with said lugs *m* and cause the cleaner-plate to revolve with said cup.

6. The wedge-shaped button *G* upon the exterior bottom of the frame *A*, combined with the stud *B*, projecting downward from the feeder *F* through the central opening of the frame *A*, substantially as set forth.

7. The bed-frame *A*, provided with the peripheral flange *d*, projecting upward therefrom, combined with the cup or trough *E*, provided with a circular rib, *u*, whereby said cup *E* is seated and centered upon said flange, as set forth.

8. The feeder *F*, having a projecting elliptical arm, as shown, and sharpened along its edge *h*, substantially as set forth.

RICHARD B. SHELDON.
JOSEPH V. PEACOCK.
